GRINDING APPARATUS

Frank J. Woidka, Saginaw, Mich., assignor to Saginaw Machine and Tool Company, Saginaw, Mich., a corporation of Michigan

Application October 11, 1957, Serial No. 689,701

19 Claims. (Cl. 51—127)

This invention relates to grinding apparatus and more particularly to grinding apparatus especially adapted automatically to grind single point carbide tools to any one of a number of predetermined profiles.

The grinding of tools with which the invention is concerned heretofore has been largely a matter of skill on the part of the machine operator. That is, a tool grinder charged with the responsibility of producing a tool having a particular profile would be required to devote substantially constant attention to the grinding operation in order to position the workpiece relatively to the grinding wheel in such manner as to shape the end of the workpiece according to the predetermined profile. Due to human frailties it is almost impossible to produce a number of tools in this manner having identical profiles and, with the advent of automation equipment requiring the use of a large number of identical tools, small differences in supposedly identical tools can lead to large numbers of unacceptable products which must either be reworked or scrapped.

Apparatus constructed in accordance with the invention includes tool holder means which is mounted for movement relative to a grinding wheel, the movement of the tool holder being controlled by a template having predetermined cam contours thereon effective to move the tool holder automatically to and from a number of positions so as to produce the desired profile on the tool held by the tool holder. The apparatus also includes means for automatically feeding the tool to the grinding wheel so as to enable the grinding operation to be completely automatic once it has been initiated. Because of the mechanical positioning and feeding of the workpiece, successive tools each having a profile formed according to a selected template will be identical. To provide the apparatus with a large degree of flexibility provision is made for the substitution of templates having different cam contours so as to enable tools having different profiles to be produced by the same machine merely by the substitution of templates.

An object of the invention is to provide tool-grinding apparatus capable of grinding successive tools to identical profiles.

Another object of the invention is to provide tool grinding apparatus of the kind referred to having tool holding means movable relatively to a grinding wheel under the influence of a template having cam surfaces thereon formed in such manner as to effect movements of the tool holder to grind a predetermined profile on the tool.

A further object of the invention is to provide tool grinding apparatus of the kind referred to adapted to grind a large number of different profile tools.

Another object of the invention is to provide a tool grinding machine of the character described and including means for automatically feeding a tool to a grinding wheel.

Other objects and advantages of the invention will be pointed out specifically or will become apparent from

2

the following description when it is considered in conjunction with the appended claims and the accompanying drawings, in which:

Figure 1 is a fragmentary, partly sectional and partly top plan view of a grinding machine constructed in accordance with the invention, the view being taken generally along the line 1—1 of Figure 2;

Figure 2 is a partly sectional and partly side elevational view of the machine and disclosing the relation 10 of the tool holder to a grinding wheel, the sectional view being along the line 2—2 of Figure 1;

Figure 3 is a view partly in front elevation and partly in section, the section being taken along the line 3—3 of Figure 2;

Figure 4 is an enlarged sectional view of the tool holder and its associated supporting apparatus;

Figure 5 is a fragmentary, enlarged top plan view of the apparatus shown in Figure 4;

Figure 6 is a schematic wiring and piping diagram 20 showing the apparatus for effecting movements of the tool holder;

Figures 7—10 are plan views of typical tools and the templates used in the grinding thereof;

Figure 11 is a fragmentary, partly sectional and partly 25 plan view of a modified part of the apparatus; and

Figure 12 is a sectional view taken along the line 12—12 of Figure 11.

Apparatus formed in accordance with the illustrative embodiment of the invention disclosed in Figures 1—6 30 of the drawings may comprise a base 1 composed of a bed 2 adapted for connection to a suitable pedestal or the like (not shown) and including a housing 3 fastened to the bed 2 in a suitable manner such as by bolts 4. Mounted on the bed 2 by suitable means such as bolts

35 5 (see Fig. 1) is a carriage support 6 having upstanding arms 7 at each of its four corners and in each of which is mounted a substantially horizontally extending shaft 8 on which is journaled a roller 9. A carriage member 10 is mounted on the rollers 9 for reciprocating movements along a path fore and aft of the machine bed in a substantially horizontal plane. At each of the four corners of the carriage 10 is an upstanding member 11 which is beveled as at 12 and which is provided with a bearing block 13 which bears against a roller 14 journaled on a shaft 15 mounted in the adjacent support 7, the arrangement being such that the rollers 14 overlie the carriage 10 and guide the latter in its movements.

Between the front and rear sets of members 11, the carriage 10 is provided with a dropped center 16 (see 50 Fig. 2) on which is mounted a pair of spaced apart rails 17 extending parallel to one another and in a direction substantially normal to the path of movement of the carriage. Each of the rails 17 is grooved as at 18 for the reception of two pairs of rollers 19, each of the rollers being journaled on a shaft 20 mounted in a slide 21. The construction and arrangement of the parts thus far described are such that the carriage 10 is capable of reciprocating movement fore and aft of the machine, whereas the slide 21 is capable of movement with the carriage and also is capable of reciprocating movement from side to side relative to the carriage.

Referring again principally to Fig. 2, the carriage 16 is provided adjacent to its rear edge and substantially intermediate the rear supporting members 11 with a tubular casing 22 equipped at its lower end 23 with a ball-race assembly 24 and at its upper end 25 with a similar ball-race assembly 26 by means of which a spindle 27 is rotatably mounted. The upper end 28 of the spindle extends through an opening 29 in the housing 3 and projects beyond the latter, the opening 29 being considerably larger than the diameter of the spindle 27 for a purpose presently to be explained. The opening 29 is

65 70

surrounded by an upstanding boss 30 in the upper surface of which is mounted a dust-sealing ring 31.

Tool holding means designated generally by the reference character 32 includes a mounting or crank arm 33 which receives the projecting end 28 of the spindle 27 and is fixed relatively to the latter by suitable means such as a set screw 34. The arm 33 includes a depending skirt 35 which overlies the boss 30 to assist in preventing the entry of grinding dust to the interior of the housing 3. The tool holder mounting arm 33 extends radially from the spindle 27 and is provided adjacent to its outer end with a tool indexing device 36 on which is mounted a tool holder 37 adapted to present one end of a tool T to a rotatable grinding wheel W which may be mounted at the end of a rotatable shaft 38 driven by suitable motor (not shown). The grinding wheel and its driving shaft 38 preferably are so mounted that the plane of the grinding wheel is at an angle to the vertical as is shown in Fig. 2 so as to enable the tool to be provided with the proper degree of rake. The grinding wheel W may be supported by a machine separate from the apparatus forming the invention, or, alternatively, the grinding wheel and its driving shaft 38 may be mounted on a pair of supports 39 fixed to the housing 3 (see Fig. 3), in which event suitable means will be provided for locating the grinding wheel in substantially the position shown in Fig. 2 and, if desired, oscillating the grinding wheel from side to side to promote even wear of the grinding surface. This mechanism forms no part of the invention per se and, hence, is not shown in more detail.

Referring particularly to Figs. 1 and 2, the slide member 21 is provided with a central web portion 40, the upper surface of which is substantially horizontal and is equipped with tapped openings for the reception of threaded screws 41 by means of which a plate-like template or cam plate 42 may be removably secured to the slide 21. The particular template 42 shown in Fig. 1 has cam surfaces 43, 44, 45, 46, and 47 on its rear edge and cam surfaces 48, 49, 50, 51, 52, and 53 on its front edge, the two cam edges being at opposite sides of the body portion 54 of the template 42. The particular configuration of the template 42 is so designed as to produce a tool T having the profile shown in Fig. 5 and about which more will be said subsequently.

The cam carrying slide 21 is accessible for the purpose of changing templates by the provision of an opening 55 in the housing 3, the opening 55 being closed during operation of the apparatus by a removable cover plate 56 which prevents the entry of grinding dust to the interior of the housing.

As is best shown in Figs. 1 and 2, the front wall of the housing 3 is provided with a tubular element 57 in which is slidably mounted a reciprocable part 58 carrying at its inner end a cam follower or roller 59 journalled on a pin 60, the part 58 being movable under the influence of a hand wheel 61 to and from positions in which the cam roller 59 bears against the rear edge of the template 42. The cam follower 59 may be set to the desired position and checked by means of a pointer 62 adapted to be read in conjunction with an indicia-carrying element 63 which rotates with the hand wheel 61.

At a point in line with the line of action with the cam follower 59, but arranged to bear against the opposite side of the template 42 is another cam follower or roller 64. The follower 64 is journalled on a shaft 65 mounted at the inner end of a reciprocable plunger 66 which is mounted for sliding movements fore and aft of the machine adjacent to the upper end of the tubular spindle housing 22. The plunger 66, during operation of the machine, is constantly urged in a direction to cause the cam follower 64 to bear against the rear edge of the template 42 by a piston 67 of a hydraulic or pneumatic cylinder 68 of known construction and which will be de-

scribed in greater detail hereinafter. A second cylinder 69 of similar construction is mounted on the housing 3, its piston rod 70 extending through an opening 71 in the housing and located so as to bear against the rear edge of the carriage 10 for a purpose presently to be explained.

Means is provided for interconnecting the plunger 66 and the spindle 27 to impart rotation to the latter and, consequently, to the tool holding means 32 upon movement of the plunger 66 relative to the carriage 10. In the illustrative embodiment of the invention the connection between the plunger 66 and the spindle 27 is effected by flexible steel tapes 72, 73, and 74, the strip 72 having one of its ends anchored to the plunger 66 by a pin 75 and its upper end passed around a portion of the spindle and anchored to the latter by a pin 76. Corresponding ends of the steel tapes 73 and 74 are passed around a portion of the spindle 27, but in an opposite direction to the direction in which the tape 72 is wrapped, the ends of the tapes 73 and 74 being fixed to the spindle by pins 77. The other ends of the steel tapes 73 and 74 are anchored to corresponding ends of pins 78 which extend through ears 79 mounted on the plunger 66. The other ends of the pins 78 are headed as at 80 and reacting between the heads 80 and the ears 79 are springs 81 which tension the tapes 73 and 74. The connection of the plunger 66 to the spindle 27 is such that reciprocating movement of the plunger will impart rotary motion to the spindle 28 and the rotary motion will be effected without backlash.

Still referring principally to Figures 1 and 2, a pressure fluid responsive device 82 of known construction is mounted by means of brackets 83 (Fig. 2) on the dropped bottom portion 16 of the carriage. The device 82 comprises a cylinder 84 having a reciprocable piston 85 mounted therein, the latter being connected by a piston rod 86 to an end wall 87 of the slide 21. The pressure fluid responsive device 82 is connected in a manner presently to be described to a source (not shown) of pressure fluid so as to effect reciprocating movement of the slide 21 and the template 42 along a path at right angles to the path of movement of the carriage 6. At the end of a stroke to the left, as viewed in Fig. 1, a switch operator 88 strikes a contact arm 89 of a limit switch 90 which reverses the movement of the slide 21 in a manner presently to be described so as to drive the slide and the template 42 to the right as viewed in Fig. 1. At the end of the stroke to the right, the end of the piston rod 86 strikes a contact arm 91 of a second limit switch 92 which causes the cam slide 21 again to move towards the left.

Apparatus for actuating the cylinder parts 67 and 70 and effecting reciprocating movement of the cam slide 21 is diagrammatically illustrated in Fig. 6 and includes a hose or tube 93 connected at one end to a source (not shown) of pressure fluid and at its other end to a solenoid operated valve 94 of known construction. The solenoid armature 95 is provided with a winding 96 having one of its ends connected by a wire 97 to a source of suitable electric power such as 110 volt 60 cycle alternating current. The other end of the winding 96 is connected to the power source through a main switch 99.

From the valve 94 lead two conduits 100 and 101, the conduit 100 communicating with the cylinder 68 at that end of the latter which is mounted nearer the housing 3, whereas the conduit 101 is similarly connected to the cylinder 69. A branch conduit 102 interconnects the opposite end of the cylinder 68 to the conduit 101 and a similar branch conduit 103 interconnects the opposite end of the cylinder 69 to the conduit 100. The arrangement of the parts thus far described is such that when the parts of the valve 94 are located to deliver pressure fluid through the conduit 101, the piston rod 67 and the plunger 66 are urged in a direction towards the template 42, and the piston rod 70 is urged in the opposite direc-

tion. When the parts of the valve 94 are in their other positions, as determined by the position of the switch 99, pressure fluid is supplied to the line 100 so as to effect movement of the piston rods 67 and 70 in directions opposite to those just referred to. The significance of the cylinder 69 and its associated piston rod 70 will be pointed out in the discussion of the operation of the apparatus.

Branching off from the line 101 is a hose 104 which leads to a solenoid operated valve 107, the latter having a pair of conduits 108 and 109 which lead to opposite ends of the cylinder 84. The valve 107 includes two solenoids, the armature 110 of one including a winding 111 having one of its ends connected by a wire 112 to a switch 99a and thence to a source of 110 volt 60 cycle alternating current and its other end connected by a wire 113 to the contact arm 91 of the switch 92. The other contact of the switch 92 is connected by a wire 114 to the power source. The armature 115 of the other solenoid in the valve 107 has a winding 116 therearound, one end of which is connected by a wire 117 to the wire 112 and the other end of which is connected by a wire 118 to a contact of the limit switch 90. The contact arm 89 of the switch 90 is connected by a wire 119 to the wire 114.

The operation of the valve 107 is such that, when the switch operator part 88 on the slide 21 closes the switch 90, pressure fluid, such as air, from the line 104 passes through the valve 107 and into the cylinder 84 to move the piston 85, the piston rod 86, and the template 42 to the right as viewed in Fig. 6. As the piston moves to the right, air is exhausted from the opposite end of the cylinder 84 through the line 108, and then through the valve 107 to atmosphere. When the end of the piston rod 86 strikes the switch 92, air is admitted through the valve 107 to the cylinder 84 through the line 108 to effect movement of the piston 85 in the opposite direction. During the latter movement of the piston, air from the cylinder 84 is exhausted through the line 109 to the valve 107 and then to atmosphere.

To condition for operation the apparatus thus far described, a workpiece to be formed into a tool having a profile similar to that shown in Fig. 5 is mounted in the tool holder in a manner presently to be described and a template corresponding to the template 42 secured to the slide 21. Thereafter, the handwheel 61 is adjusted to position the cam follower 59 in engagement with the front cam face of the template 42 and the plunger 66 is moved inwardly by the piston rod 67 so that the cam follower 64 bears against the opposite cam surface of the template. If the position of the slide 21 is such that the cam follower 59 bears against the cam surface 49 just to the left of the bevelled surface 48, and the cam follower 64 bears against the cam surface 43, the position of the tool holder will be such that the tool T is so located as to have the profile surface 43a ground on the end thereof. As the template 42 progresses toward the right, as viewed in Fig. 1, the tool will continue to be held in this position until such time as the cam follower 64 engages the cam surface 44. At this point the slide 66 will be forced rearwardly of the machine and the rearward movement of the slide 66 will impart counterclockwise rotation to the spindle 27, as viewed in Fig. 1, and consequently, counterclockwise rotation to the tool T, about a point which lies substantially on the axis of rotation of the spindle 27. As the plunger 66 is pushed rearwardly by the cam surface 44, the tool holder will be swung relatively to the grinding wheel so as to grind a radius 44a on the end of the tool. The length of the radius 44a will be determined by the length of the surface 44.

When the movement of the slide 21 and the template 42 has progressed to the point where the cam follower 64 is ready to traverse the cam surface 45, that is, the position of the parts shown in Fig. 1, further movement

of the slide 21 to the right will grind a flat surface 45a on the end of the tool T. When the movement of the slide 21 and the template 42 has progressed to the point where the cam follower 64 is about to traverse the cam surface 46, the cam follower 59 will be in a position to traverse the cam surface 50. At this point, the force exerted on the template 42 by the pressure cylinder 68 will effect forward movement of the carriage 10 relative to the base 1 until such time as the cam follower 59 is 10 in engagement with the cam surface 51. The forward movement of the carriage 10 will effect movement of the tool holder away from the grinding wheel W so as to prevent grinding of the tool during this phase of operation of the apparatus. During the time that the tool is 15 out of engagement with the grinding wheel W, the movement of the slide 21 under the influence of the pressure device 82 will continue so as to cause the cam follower 64 to traverse the cam surface 46. Thus, the plunger 66 will be forced rearwardly relatively to the carriage 10 20 so as to effect counterclockwise rotation of the spindle 27 and, consequently, counterclockwise rotation of the tool holder. During the rotation or swinging of the tool holder, the cam follower 59 will be traversing the cam surface 52, thereby forcing the carriage 10 rearwardly 25 to return the tool into engagement with the grinding wheel. When the movement of the slide 21 has progressed to the point where the cam follower 59 traverses the cam surface 53 and the cam follower 64 traverses the cam surface 47, the tool again will be in contact 30 with the grinding wheel to grind a flat surface 47a thereon. Inasmuch as the tool was not in engagement with the grinding wheel during the swinging of the tool, the relation of the surfaces 45a and 47a will be angular. 35 That is, between the surfaces 45a and 47a will be an angle 46a as opposed to a radius.

As is best shown in Fig. 1, the cam surfaces 49 and 53 do not lie in the same vertical plane, but, rather, the cam surface 53 is offset forwardly with respect to the cam surface 49. The effect of the offset is that the point 40 about which the tool is swung is moved laterally, but remains on the axis of the spindle 27.

When the slide 21 has completed its movement to the right, as viewed in Fig. 1, the end of the piston rod 86 will trip the switch 92 to cause movement of the cam 45 slide 21 towards the left. As the slide moves to the left, the cam followers 59 and 64 will re-traverse the several cam surfaces and will cause the tool to be swung in a direction opposite to that previously described so as to present the several profile surfaces of the tool to the 50 grinding wheel for further grinding. At the end of its left hand stroke, the switch operator 88 will actuate the switch 90 to cause movement of the slide 21 again to the right.

Referring now more particularly to Figs. 4 and 5, the 55 tool holding means 32 disclosed therein for purposes of illustration comprises a shaft 125 journalled for rotation at the radially outer end of the tool holder supporting arm 33. In assembled relation, the shaft 125 extends vertically and carries at its upper end an eccentric part 126 which is received in an opening 127 formed in a block 128. To rigidify the connection of the parts, the arm 33 is provided with an upstanding tubular boss 129 which, in turn, is provided with a reduced diameter extension 130 which is received within an opening 131 60 in communication with the opening 127. A thrust bearing 132 surrounds the shaft 125 and is seated on the base of the opening 127 to assure retention of the shaft in its proper location.

The opening 127 is provided with a recess 133, in 70 which is located a roller 134 rotatably mounted on a shaft 135 which is secured to the block 128 by means of a threaded nut 136. The block 128 is provided on its upper surface with a dovetail 137 (see Fig. 3) on which is slidably received a correspondingly slotted tool holding element 138, the latter including upstanding

sidewalls 139 between which the tool T may be placed and secured by wedges or shims 140. The position of the tool holding element 138 may be held in adjusted relation relative to the block 128 by means of dowels 141 and setscrews 142 (see Fig. 4).

At the lower end of the shaft 125 is fixed, by means of a pin 143, and adjusting wheel 144 which is operable to impart rotation to the shaft 125. Rotation of the shaft 125 will cause the eccentric part 126 to bear against the roller 134 to effect movement of the parts 128, 139 and T towards and away from the grinding wheel a distance corresponding to the difference in diameters of the extension 130 and the opening 131. The aforementioned parts of the head 37 are moved away from the grinding wheel upon rotation of the shaft 125 in a direction to disengage the eccentric part 126 from the roller 134 by the operation of reeds 145 formed of spring steel or the like and secured to the arm 33 and the block 128 by shim blocks 146 and 147, respectively.

It is preferred that the rotation of the shaft 125 in a direction to feed the tool T towards the grinding wheel be effected automatically during operation of the machine and this may be accomplished by the provision of the indexing device 36. The indexing device 36 comprises a toothed ratchet wheel 148 fixed on the shaft 125 by means of a pin 149, the device 36 also including an arm 150 loosely mounted on the shaft 125 and having pivoted at its outer end, as at 151, a pawl 152 which is urged by a spring 153 into engagement with the teeth of the ratchet wheel 148. The arm 150 normally is maintained in the position shown in full lines in Fig. 5 by means of a spring 155 having one of its ends anchored to a hook 155a fixed on the arm 150 and its other end anchored to a post 155b mounted on the crank arm 33. When, however, the tool holder 37 has been rotated to a position it must occupy to grind the tool profile surface 47a, the arm 150 will engage an adjustable stop member 156 which is mounted on a bracket 157 secured to the upper wall of the housing 3 by suitable means such as a bolt 158, and the engagement of the arm 150 with the stop 156 will effect clockwise rotation of the ratchet wheel 148, as viewed in Fig. 5, and, consequently, corresponding rotation of the shaft 125 so as to cause the eccentric 126 to bear against the roller 134 and move the assembly 37 towards the grinding wheel. When the tool holder is rotated away from the adjusting part 156, the spring 155 will return the arm 150 to its normal or inactive position, but the ratchet wheel 148 will remain in adjusted position under the influence of a locking pin 159 which is yieldably urged into engagement with the teeth of the ratchet wheel by a spring 160 which reacts against the pin 159 and a threaded stop 161 mounted in the arm 33.

After the tool T has been ground, it may be removed from the holder and another workpiece positioned therein. The second workpiece will be ground to the identical profile of the tool T, as will successive workpieces, as long as the template 42 is used to control the movements of the tool holder. Accordingly, large numbers of identical workpieces may be formed without relying heavily on the skill of the operator of the machine.

Apparatus constructed in accordance with the invention is capable of producing a wide variety of tools. Illustrative examples of tools capable of production on the apparatus are shown in Figs. 7-10. In each instance, the profile of the tools T¹, T², T³, T⁴, is produced by the templates 42a, 42b, 42c, 42d, respectively, each of which is shown immediately to the right of the tool, and it should be noted that tools having profiles formed by angles, radii, or combinations thereof may be produced merely by the utilization of the proper

template. The examples shown in Figs. 7-10 are intended to illustrate the flexibility of apparatus constructed in accordance with the invention and are not to be construed as limiting the use of the apparatus to the production of the particular tools shown.

When it is desired to change templates, the slide 21 should be moved far enough to the left, as viewed in Fig. 1, to enable the cam follower 59 to engage the bevelled cam surface 48 of the template. The slide may be maintained in this position opening the switch 99a in the line 112. Thereafter, the switch 99 may be opened to effect movement of the parts of the valve 94 to such positions that pressure fluid is exhausted from the cylinder 68 through the line 102 and is admitted to the cylinder 69 through the line 103 so as to project the piston rod 70 forwardly and retract the piston rod 67 and the plunger 66. The retraction of the piston rod 67 will disengage the cam follower 64 from the template 42 and the projection of the piston rod 70 will cause the latter to push against the carriage 10. Thereafter, the handwheel 61 may be revolved to retract the cam follower 59. As the cam follower 59 is retracted, the carriage 10 will be moved forwardly until it strikes a stop (not shown), thereby positioning the template 42 in a position easily accessible through the opening 55 in the housing 3. At this point the template securing parts 41 may be withdrawn and another template substituted for the template 42. During the substitution, the piston rod 70 will hold the carriage in locked position. After the substitution of templates has been made, the apparatus may be conditioned for operation in the manner previously described and used to form a tool of predetermined profile.

In Figures 11 and 12 there is disclosed alternative apparatus for effecting rotation of the spindle and, consequently, the tool holder. In the modified construction, the tubular casing 22 is provided with a pair of guideways 163, 164 in which is mounted a corresponding pair of toothed rack elements 165, 166. The rack elements are mounted for reciprocating movement in the guideways and are supported in the latter by anti-friction balls 167. One end of the rack element 165 is bifurcated for reception of the cam follower roller 64 which bears against the template 42 in the same manner as previously discussed, whereas the opposed end of the rack section 166 is abutted by the end of the piston rod 67. The spindle 27a is provided with a plurality of longitudinally extending teeth 168 which are so arranged as to mesh with the teeth 169 of the rack elements 165 and 166. The arrangement of the several parts is such that fluid pressure acting on the piston rod 67 causes movement of the rack section 166 to the right, as viewed in Figure 11, so as to impart counterclockwise rotation to the spindle 27a. Rotation of the shaft 27a in counterclockwise direction will effect movement of the rack element 165 towards the right, as viewed in Figure 11, so as to cause the cam follower 64 to bear against the template 42 and locate the tool holder in such position as to grind the desired profile surface on the latter. When the contour of the template 42 is such as to effect movement of the rack 165 to the left, as viewed in Figure 11, the rotation of the spindle 27a will be reversed.

The construction and arrangement of the toothed spindle 27a, the co-operating rack elements 165, 166, and the template 42 are such that force is applied to one of the rack elements in one direction and force is applied to the other rack element in the opposite direction. As a result, rotation of the spindle 27a may be effected in either direction without backlash.

The disclosed embodiments are representative of presently preferred forms of the invention but are intended to be illustrative rather than definitive thereof. The invention is defined in the claims.

I claim:

1. Apparatus for grinding one end of a tool to a predetermined profile comprising a base; a carriage mounted on said base for movements along a reciprocating path relative to said base; a spindle; means journaling said spindle in said carriage for rotation relative thereto; a tool holder for presenting said one end of a tool to a grinding wheel; means mounting said tool holder on said spindle for rotation therewith; a slide; means mounting said slide on said carriage for reciprocating movements relative to the latter along a path substantially normal to the path of movement of said carriage; a template having a pair of cam surfaces thereon; means mounting said template on said slide for movement therewith; means reacting between said base and one of said cam surfaces during movement of said slide for imparting movement to said carriage; means reacting between the other cam surface and said base and including a connection to said spindle for imparting rotation to said spindle during movement of said slide; and means connected to said slide for moving the latter.

2. Apparatus as set forth in claim 1 wherein the means mounting the template on said slide are removable for enabling any one of a number of different templates to be used so as to produce a number of tools having different profiles.

3. Apparatus as set forth in claim 1 wherein said means reacting between said base and said one cam surface includes support means mounting said support on said base, and a cam follower mounted on said support in engagement with said one cam surface.

4. Apparatus as set forth in claim 3 wherein the mounting means for said support is adjustable relatively to said base.

5. Apparatus as set forth in claim 1 wherein the means reacting between said base and said other cam surface includes slidable plunger means, and means for urging said plunger means towards said other cam surface.

6. Apparatus as set forth in claim 5 wherein the end of said plunger means adjacent to said other cam surface carries a roller.

7. Apparatus as set forth in claim 5 wherein said plunger means comprises a pair of toothed rack elements having their teeth in mesh with teeth on said spindle, one of said rack elements being in engagement with said urging means and the other being in engagement with said other cam surface.

8. Apparatus as set forth in claim 5 wherein said connection to said spindle includes a flexible band having one end anchored to said plunger means and its other end passing around and anchored to said spindle, and another flexible band having one of its ends anchored to said plunger means and its other end passing around and anchored to said spindle, said bands extending in an opposite direction from said spindle and being oppositely passed around said spindle.

9. Apparatus as set forth in claim 1 wherein the tool holder mounting means includes a crank arm fixed to said spindle and extending radially therefrom, and an indexing device secured to said arm and to said tool holder.

10. Apparatus as set forth in claim 9 wherein said tool holder is so supported by said indexing device and said arm that a tool held in said tool holder may have its said one end located at and rotated about a point substantially on the axis of rotation of said spindle.

11. Apparatus as set forth in claim 9 wherein said indexing device comprises a shaft journalled on said arm, one of the ends of said shaft having an eccentric thereon in engagement with said tool holder, and means connected to said shaft for rotating the latter, said eccentric bearing against said tool holder to effect relative movement of said tool holder and said arm.

12. Apparatus as set forth in claim 11 wherein the

means for rotating said shaft includes a ratchet mechanism.

13. Apparatus as set forth in claim 11 including yieldable means interconnecting said tool holder and said arm.

14. Apparatus for grinding one end of a tool to a predetermined profile comprising a carriage; means supporting said carriage for reciprocating movement along a path towards and away from a grinding station; a slide; means supporting said slide on said carriage for reciprocating movements of the slide along a path substantially normal to the path of said carriage; a spindle; means mounting said spindle on said carriage for rotation relative thereto; a tool holder; means mounting said tool holder on said spindle for rotation with the latter; means connected to said slide for effecting reciprocating movements thereof; a template having a pair of opposed cam surfaces thereon; means mounting said template on said slide; a first cam follower mounted to follow one of said cam surfaces; a second cam follower mounted to follow the other cam surface; and means connecting one of said cam followers to said spindle for translating movement of said one cam follower into rotation of said spindle and said tool holder.

15. Apparatus for grinding one end of a tool to a predetermined profile comprising a base; a carriage mounted on said base for movements along a reciprocating path relative to said base; a spindle; means journaling said spindle in said carriage for rotation relative thereto; a tool holder for presenting said one end of a tool to a grinding wheel; means mounting said tool holder on said spindle for rotation therewith; a slide; means mounting

30 said slide on said carriage for reciprocating movements relative to the latter along a path substantially normal to the path of movement of said carriage; a template having a pair of cam surfaces thereon; means mounting said template on said slide for movement therewith; a first cam follower; means mounting said cam follower to follow one of said cam surfaces; a second cam follower; means mounting said second cam follower to follow the other cam surface; means connecting one of said cam followers to said spindle for translating movement of said one cam follower into rotary movement of said spindle and the tool holder; and means connected to said slide for moving the latter.

35 16. Apparatus as set forth in claim 15 wherein said one of said cam followers comprises a plunger mounted for reciprocating movement.

40 17. Apparatus as set forth in claim 15 wherein the means connecting said one of said cam followers and said spindle comprises a flexible band having one of its ends anchored to said plunger and its other end passed around and anchored to said spindle, and another flexible band having one of its ends anchored to said plunger and its other end passed around and anchored to said spindle, said bands extending in opposite directions from said spindle and being passed in opposite directions around said spindle.

45 18. Apparatus as set forth in claim 16 wherein the means connecting said one of said cam followers and said spindle comprises teeth on said plunger and corresponding teeth on said spindle.

50 19. Apparatus for grinding one end of a tool to a predetermined profile comprising a base; a housing supported on said base; a carriage mounted on said base within said housing for reciprocating movement along a path fore and aft of said base; a spindle journalled in said carriage for rotation relative thereto; a tool holder; means mounting said tool holder on said spindle for rotation therewith; a slide mounted on said carriage for reciprocating movement along a path substantially normal to the path of movement of said carriage; a template having a pair of opposed cam surfaces thereon; means mounting said template on said slide for movement therewith; a first cam follower mounted in said housing for engagement

with one of said cam surfaces; a second cam follower slidably mounted in said carriage for engagement with the other cam surface; means connecting said second cam follower to said spindle for translating sliding movement of said second cam follower to rotary movement of said spindle; and means connected to said slide for effecting movement of the latter relative to said cam followers.
